UNITED STATES PATENT OFFICE.

HERBERT AUSTIN, OF ERDINGTON, NEAR BIRMINGHAM, ENGLAND.

WATER-COOLING SYSTEM FOR EXPLOSION-MOTORS.

SPECIFICATION forming part of Letters Patent No. 769,582, dated September 6, 1904.

Application filed August 6, 1902. Serial No. 118,616. (No model.)

To all whom it may concern:

Be it known that I, HERBERT AUSTIN, a subject of the King of Great Britain, residing at Erdington, near Birmingham, England, have 5 invented certain new and useful Improvements in Water-Cooling Systems for Explosion-Motors, of which the following is a specification.

This invention relates to means for cooling the cylinder and valve-chest of an internal- 10 combustion engine, and particularly of such an engine when employed as a motor for a self-propelled vehicle. In this class of engines it is the common practice to cool the cylinders and other heated parts by effecting 15 circulation of water through jackets about the same, and the present invention is embodied in means for cooling with air this jacket-water as it is circulated. This means comprises in part an apparatus in which the wa- 20 ter from the jackets flows to and fro through a connected series or system of gilled cooling-pipes between two upright headers or chambered tanks of relatively small capacity which serve to change the direction of the 25 zigzag flow through the cooling-pipes and insure that the system is kept full of water. The hot water from the jackets enters the upper part of the system of cooling-pipes and flows downward from one to the other to the 30 pump, which forces it again into the jackets.

Another feature of the invention is the means provided for permitting the steam and air to escape to the atmosphere from the chambers in the said upright headers or tanks. 35 In the partitions which separate the super-posed chambers are small and always open apertures, which permit the air and steam to rise to the upper chamber of the series, and from this chamber the air and steam escape 40 through a restricted outlet to the atmosphere. The cooling-water is supplied to the cylinder-jacket and valve-chest jacket through separate conduits, whereby each is supplied with water at substantially the same temperature, 45 and an auxiliary set of cooling-pipes is supplied for preliminarily reducing the temperature of the water from the valve-chest jacket

before it enters the main system of cooling-pipes.

The invention is illustrated by the drawings herewith, of which—

Figure 1 is a longitudinal section through a cooling apparatus constructed according to this invention, showing a pair of motors in side elevation. Fig. 2 is a plan view of the 55 cooling apparatus and motors; and Fig. 3 is a rear elevation of the cooling apparatus—that is to say, looking in the direction of the arrow, Fig. 1—and shows the motor-cylinders and their jackets in transverse section. 60

Two vertical headers on tanks A A' of small horizontal section are fixed at opposite sides of the motor-car, and communicating between these tanks are a number of cooling-pipes B B', &c., in position one above another, 65 each of which passes for some distance along each side of the car and passes also across the front thereof. These cooling-pipes are provided with gills b, as is usual with water-cooling pipes. The tank A has horizontal partitions 70 a, which divide it into a number of super-posed compartments, and the tank A' is similarly divided by horizontal partitions a', which alternate in their positions with the partitions a into one more compartment in number 75 than those of the tank A. The top cooling-pipe B communicates with the uppermost compartments of the tanks. The next pipe 70 communicates with the uppermost compart- 80 ment of the tank A and the second compart- ment of the tank A', the third pipe with the second compartment of the tank A' and with the second compartment of the tank A, and so on, as shown, the lowest pipe communicat- 85 ing with the lowest compartments of the tanks.

The motor-cylinders K K' are arranged, preferably, at a lower level than the cooling system in order that the cooling may be effected to some extent by a natural circulation should the pump fail. The water flows from 90 the bottom of the tank A' through a pipe c into the circulating-pump C and is forced by the pump through pipes d and e into the bottom of the water-jacket of the motor-cylinder

K and through the pipe *d* and through a pipe *f* into one side of the water-jacket E of the valve-chest of such cylinder. The two valve-chest jackets E E' are connected by a pipe *i*, and the two cylinder-jackets are connected by a passage *g*.

The hot water flows from the top of the jacket of the cylinder K' through a pipe *h* into a pipe D and thence into the uppermost compartment of the tank A'. It then passes through the pipe B into the uppermost compartment of the tank A, thence through the pipe B' into the second compartment of the tank A', thence through the pipe B² into the second compartment of the tank A, and so on, finally passing from the lowest compartment of the tank A through the pipe B³ into the lowest compartment of the tank A', thus completing the cycle of the water which passes through the cylinder-jackets.

The hot water from the jackets E E' of the valve-chests flows out from the side of the jacket E' through a pipe *k* to an auxiliary system of cooling-pipes F and through them by the pipe D to the uppermost compartment of the tank A', from whence it flows, with the water from the cylinder-jackets, through the cooling-pipes B B', &c., to the lowest compartment of the tank A', thus completing the cycle of the water which passes through the valve-chest jackets.

The tanks A A' being carried some distance above the level of the upper pipe B insures that if a proper supply of water is poured into either tank the cooling pipes and jackets will be kept full of water for a considerable time; but owing to the provision hereinafter described for the escape of steam water will of course require to be added from time to time.

Openings *l* of a size only which will not substantially interfere with the circulation of the water are formed in the partitions *a a'* of the tanks A A' to allow air or steam to pass into the uppermost compartments. Any excess of air or steam which may collect in the tank A' will pass through the radiating-pipe B to the tank A. Pipes *m*, which for convenience may be brought out at the bottoms of the tanks A A', as shown, communicate, respectively, with the compartments at the tops of the tanks and allow air and steam to escape and also act as overflows. The tanks A A' have openings in the tops covered by screw-caps. The water may thus be supplied to either tank. There may of course be a single motor-cylinder only, if desired. The two tanks may, if desired, be divided into the same number of compartments as would be the case, for instance, if the lowest partition *a'* of the tank A' were removed. In such case the pipe B³ might be dispensed with, and the water would pass from the bottom of the tank

A to the cooling-jackets without passing again through the tank A'.

Special features of the invention are the circulation of the water through a cooling system by passing it successively through pipes which follow one another in a descending order and the means provided for the escape of steam and air at the points where the water flows from the end of one pipe of a cooling system into the end of the next pipe of the system. The purpose in superposing the pipes of the cooling system and connecting the upper end with the outlets of the jackets is to utilize the heat for assisting in the circulation of the water through the system or coil.

Having fully described my invention, what I claim, and desire to secure by Letters Patent, is—

1. In means for the purpose specified, the combination with the cylinder and valve-chest jackets of an internal-combustion engine, of a plurality of main cooling-pipes connected in a superposed system, one end of said system of pipes being connected with the outlet of the cylinder-jacket, thereby receiving the full flow from the jacket, and the other end of said system of pipes being connected with the inlets of both the cylinder-jacket and valve-chest jacket, a supplementary system of cooling-pipes between and connecting the outlet of the valve-chest jacket with the inflow to the main system of cooling-pipes, and means for effecting the circulation of water through said jackets and system of cooling-pipes.

2. In means for the purpose specified, a plurality of cooling-pipes superposed in position and connected at their ends through the medium of upright headers containing superposed chambers into which the respective pipes open, thus forming a continuous conduit, and said headers, having normally open, restricted apertures in the partitions between said chambers, and a normally open outlet to the atmosphere from the upper chamber for the steam and air.

3. The combination with the cylinder-jacket and valve-chest jacket of an internal-combustion engine, of a water-cooling system of pipes connected to form a continuous water-conduit for the full flow of the water which passes through such jackets, said system being exposed to the air, pipes separately connecting the outlets of said jackets with the higher portion of said cooling-conduit, and pipes separately connecting the inlets of said jackets with the lower portion of said cooling-conduit.

4. Means for the purpose specified comprising the jacket of an internal-combustion engine, two upright headers each divided into superposed compartments by apertured par-

titions, a continuous conduit for the full flow of the water which passes through said jacket, formed by superposed pipes connecting at their ends through the respective compartments in the headers, and pipes connecting the outlet and inlet of the said jacket respectively, with the upper and lower extremities of said conduit, the upper compartments in the headers being open, normally, to the at-

mosphere for the escape of steam and air from the system.

In witness whereof I have hereunto signed my name, this 22d day of July, 1902, in the presence of two subscribing witnesses.

HERBERT AUSTIN.
